UNITED STATES PATENT OFFICE

2,674,941

ROTARY MARKING DEVICE

Charles E. Hopwood and Robert L. Winkler, Baltimore, Md., assignors to Bethlehem Steel Company, a corporation of Pennsylvania

Application September 20, 1947, Serial No. 775,196

3 Claims. (Cl. 101—212)

1

This invention relates in general to a marking device, and more particularly to a device for printing desired items of information, such as heat numbers, specification data, trade-marks, etc., at predetermined spaced intervals on continuous steel strip or other material being delivered at considerable speed by a rolling mill to a winding machine.

Heretofore it has been a usual practice to mark or stamp metal sheet or strip manually and subsequent to its removal from the mill. The possibilities or errors and of unevenly spaced markings by this method are evident, and it is also unduly wasteful of time and labor for the large tonnages produced in modern continuous mills.

One object of this invention, therefore, is to provide a device for marking flat metal sheet or strip with indelible identifying letters, numbers or symbols.

Another object is a device for automatically marking sheet or strip as it issues from a rolling mill onto a coiling device.

Another object is a continuous marking device with a dependable and even inking mechanism.

Another object is a light and simple marking device which may be adjusted either vertically or transversely at will.

Still other objects, purposes and advantages of the invention will appear hereinafter in the specification and in the appended claims.

In the annexed five (5) sheets of drawings, forming a part of this specification and in which like characters of reference indicate like parts:

Figure 1 is a side elevation of the device mounted upon the roll housing of a four-high skin pass mill, and showing the matter of printing upon strip while the latter is being coiled.

Fig. 2 is a transverse vertical section taken on the line 2—2 of Fig. 1 and showing the pneumatic control arrangement;

Fig. 3 is a side elevation of the printing mechanism;

Fig. 4 is a longitudinal horizontal section on the line 4—4 of Fig. 3;

Fig. 5 is a transverse vertical section on the line 5—5 of Fig. 3;

Fig. 6 is a transverse vertical section of the print and drive wheels, taken on the line 6—6 of Fig. 7;

Fig. 7 is a longitudinal vertical section on the line 7—7 of Fig. 6, showing the print wheel in side elevation;

Fig. 8 is a longitudinal vertical section through the ink reservoir, taken on the line 8—8 of Fig. 4;

Fig. 9 is a fragmentary transverse vertical section on the line 9—9 of Fig. 8;

2

Fig. 10 is a fragmentary top plan view of the print wheel, showing the stamp insert in place;

Fig. 11 is a transverse vertical detail section of the pivoted retracting link; and

5 Fig. 12 is a transverse detail section showing the means for laterally adjusting the position of the printing device on the lower pivot shaft.

Referring to Figs. 1 and 2 of the drawings, the reference numeral 1 designates the roll housings 10 of a conventional four-high mill, having a pair of working rolls 2 each provided with a backing roll 3. The sheet or strip 4 which is being coiled is drawn between the working rolls 2 and beneath the idle press roll 5 on the delivery side onto the tension reel or drum 6 on the floor 7 adjacent thereto. Firmly bolted on said roll housings 1 above the level of the press roll 5 are supporting brackets 8, shown in Fig. 3, in which the set-screws 9 hold a lower pivot shaft 10 between the 15 housings. Other brackets 11 bolted at a higher level on said housings 1 support an upper pivot shaft 12 in like manner.

20 Pivots mounted on said lower shaft 10, as shown in Fig. 12, by means of a pair of bushings 13 and an end-threaded spacing sleeve 14 having a pressure lubricating fitting 15 and retaining nuts 16, are a pair of vertically disposed plates 17 held in spaced parallel relation by the three 25 spreaders 18, said plates 17 constituting the side frame members of the printing device. Sliding collars 19 having set-screws 20 permit the transverse adjustment and fastening of the printing device at any desired place on said shaft 10.

30 Referring now to Figs. 6 and 7, between the side frame plates 17 a print wheel (or wheels) 21, of such diameter as to space the imprint at the desired intervals, and preferably of cast aluminum or other light metal, is keyed upon a 35 rotatable shaft 22 journaled in bearings 23 mounted between the oil seals 24 in frusto-conical housings 25 bolted upon said side frame plates 17. Referring also to Fig. 10, in a recess 26 in the peripheral edge or rim 27 of the print wheel 21 there is mounted a metal stamp holder 28, secured by a pair of wedges 29 bolted together, and holding a removable rubber stamp insert 30 with the desired inscription. Also mounted on the print wheel 21 are counterweights 31, of lead 40 or other similar metal, suitably proportioned and located to afford static balance to the print wheel 21 with the stamp insert 30 in place. Upon extending tapered portions 32 of the shaft 22 projecting beyond the bearing housings 25 are 45 mounted the drive wheels 33 and 34, their webs 50 35 being preferably dished or coned so as to slope

inward from their hubs 36 to the rims 37 as shown in Fig. 6, and said hubs 36 being secured by lock washers 38 and jam nut 39 on the threaded extremities of the shaft 22. Said drive wheels 33 and 34 have approximately the same diameter as the print wheel, and are provided with rubber tires 40 mounted on the rims 37, which tires are kept thereon by retaining rings 41 bolted to the rims and receive their driving traction by contact with the moving sheet or strip 4 being marked. The drive wheel 34 also has a large sprocket 42 bolted upon a projecting portion 43 of its hub 36. Grease or other similar lubricant is supplied to the bearings 23 by means of the pressure fittings 44.

Referring now to Figs. 4, 5, 8 and 9, a metal receptacle 45 partially filled with ink-soaked cotton waste 46 and functioning as an ink reservoir is removably secured between the side frame plates 17 by means of thumb screws 47. An ink-collecting roller 48, preferably of cast aluminum alloy or the like, is mounted on a shaft 49 journaled in bearings 50 having oil seals 51 and enclosed in housings 52 bolted on the side frame plates 17. End covers 53 and 54 mounted on said housing 52 protect the bearings 50 from dirt and grit, and a small sprocket 55 is keyed to the end 56 of the shaft 49 projecting through the end cover 54. The sprockets 42 and 55 are operatively connected together by means of an endless roller chain 57. As shown in Fig. 8, a felt pad 58 retained by a clip 59 on the bottom of a cover plate 60 fulcrumed on the inner upper lip 61 of the receptacle 45 contacts the ink roller 48 to distribute the ink uniformly and to remove excess ink. Downward pressure from a compression spring 62 which is adjustable by means of a wing nut 63 and washer 64 on a long upright carriage bolt 65 brazed to the bottom of the ink receptacle 45 holds the pad 58 and cover plate 59 in place.

Intermediately disposed between the print wheel 21 and the ink wheel 48 and engaging both said wheels is an ink-spreading roller 66, having a rubber tire 67 which transfers a thin film of marking fluid from the ink roller 48 to the type surface on the print wheel 21. As shown in Figs. 3 and 4, said roller 66 is secured by set-screws 68 on a shaft 69 journaled in bearings 70 having oil seals 71 and enclosed in housings 72 having end covers 73. Said housings 72 are mounted on side pivot arms 74, each arm having on its other end an adjusting screw 75 and a longitudinally disposed slot 76. The adjusting screw 75 is threaded through the pivot arm 74 into a pivot block 77 in the slot 76, which block 77 pivots on a stud 78, the side plates 17 being provided with a vertical slot 79 allowing movement of the shaft 69 therein. Said side plates also have a bottom cut-away portion 80 to allow for clearance of the press-roll 5. Studs 81 and 82, on each side on the pivot arm 74 and side plate 17 respectively, are connected by a tension spring 83 which maintains the contact pressure between the rollers while permitting adjustments of the thickness of the film of marking fluid.

Referring now to Figs. 1 to 3, inclusive, the device can be retracted for clearance while threading under it the material to be marked, or be raised as the coil increases in diameter, or receive an increase or decrease in marking pressure, by means of a two-way air cylinder 84, which cylinder is pivotally connected to the upper pivot shaft 12 and has a piston rod 85 pivotally connected to the top spreader 18 as shown in

Fig. 11. A conduit 86 supplies air under pressure to the four-way valve 87, which directs the inlet air either to the upper pipe 88 and hose 89 or to the lower pipe 90 and hose 91 in order to admit air to the desired end of the cylinder, and also releases the exhaust air to the atmosphere.

The present device can be adjusted transversely so as to mark the material at any point across its width. If it is desired to imprint more than one mark across the width of the material, two or more print wheels with their attached drive wheels, marking fluid rolls, etc., each supported on its own frame, can be mounted on the lower pivot shaft 10. The various print wheels, in this case, can be synchronized to maintain a set spacing between the imprints along the length of the strip material by means of a chain and sprocket drive from each print wheel to the common pivot shaft 10, which can be arranged in an understood manner to rotate freely in conventional bearings in the lower supporting brackets 8.

Although we have shown and described our invention hereinabove in considerable detail, we do not wish to be limited narrowly to the exact and specific structure and arrangements stated, but we may also use such substitutes, modifications, or equivalents thereof as are within the scope and spirit of the invention and of the appended claims.

Having thus described our invention in accordance with statute, what we claim as new and useful and desire to protect by Letters Patent is:

1. In a device for marking sheet or strip, the combination with a supporting member, of a pair of horizontal pivot shafts mounted in vertically spaced relation on said supporting member, a pair of side frame members pivotally mounted on the lower pivot shaft, a shaft rotatably journaled between the side frame members, a print wheel and friction drive wheels mounted on said shaft, a spreader connecting the tops of the side frame members, a two-way air cylinder pivotally connected to the upper pivot shaft and having a piston rod pivotally connected to the spreader, a source of fluid pressure, and conduit and valve means adapted to direct said fluid pressure alternatively either to the upper or the lower end of the cylinder and simultaneously to exhaust fluid pressure from the opposite end of said cylinder.

2. In a device for marking sheet or strip, the combination with a supporting member, of a pair of horizontal pivot shafts mounted in vertically spaced relation on said supporting member, a sleeve slidably mounted on the lower pivot shaft, side frame members secured at each end of the sleeve, adjustable collars abutting said sleeve on the lower pivot shaft, a print wheel journaled in said side frame members, and a fluid pressure cylinder slidably mounted on the upper pivot shaft and having a piston rod pivotally connected to the frame.

3. In a device for marking sheet or strip, the combination with a supporting member, of a pair of horizontal pivot shafts mounted in vertically spaced relation on said supporting member, a pair of spaced bushings on the lower pivot shaft, an end-threaded sleeve encircling said bushings, a lubricating fitting on said sleeve, side frame members at each end of the sleeve, side frame member retaining nuts on each end of the sleeve, laterally slidably collars having set-screws and abutting the retaining nuts on said lower pivot shaft, a print wheel and friction drive wheels

5

rotatably journaled in said side frame members, and an air cylinder slidably mounted on the upper pivot shaft and having a piston rod pivotally connected to the frame.
